UNITED STATES PATENT OFFICE.

JESSE E. COMBS, OF OSHTEMO, MICHIGAN.

CAR-COUPING.

SPECIFICATION forming part of Letters Patent No. 242,274, dated May 31, 1881.

Application filed February 5, 1881. (No model.)

To all whom it may concern:

Be it known that I, JESSE E. COMBS, of Osh-
temo, county of Kalamazoo, State of Michigan,
have invented new and useful Improvements
5 in Car-Couplings, of which the following is a
specification.

My invention has for its object certain im-
provements in the construction and use of car-
coupling devices, whereby greater safety and
10 convenience are effected.

In the drawings forming a part of this speci-
fication, in which similar letters of reference
indicate like parts, Figures 1 and 2 are side
15 elevations of the rear end of two cars, showing
side views of the coupling devices and draw-
bars. Figs. 3 and 4 are top views of the same.
Fig. 5 is a section and top view on dotted line
in Figs. 1 and 2. Fig. 6 is a top view of the
coupling devices, and Figs. 7 and 8 show a con-
20 struction of draw-bars for use with cars of dif-
ferent heights.

In the construction of my device, draw-bars
D, already in use, which have three connect-
ing-link receptacles in their ends c', may be
25 used by adapting the side receptacles to receive
the connecting portion h of the latches a,
(shown in Fig. 5,) which may be done by cut-
ting out the rear inclosure of said receptacles;
or a new draw-bar may be constructed. Each
30 of the receptacles is provided with a hole, e,
for the insertion of a link-pin, e. Said pin is
formed with an eye in the top for the connec-
tion therewith of chain v, which chain connects
with the draw-bar D, thus preventing the loss
35 of the pin.

The form of the latches a is plainly shown in
Fig. 5, having a hook at one end and a spring,
s, secured to the other, said spring resting
against the draw-bar D. These latches a are
40 detachably connected with the draw-bars D,
one on one side of a bar and another on the
opposite side of the bar, to be connected with

said bar by locating portion h, which is per-
forated in the side receptacle, and inserting
pin e, observing to first pass the end bearing
45 of the spring s through the rest y secured to
the side of the draw-bar D. Pins e are in-
serted in holes c at x x, around which the
hooked ends of the latches a lock.

One especial point of safety in this construc-
tion, aside from obviating danger of injury to
the operator, is that should one of the latches
or its pin become broken the cars would not
uncouple, because they would be held together
55 by the other latch, and should both latches
become inoperative on the journey the old link
N (shown in Fig. 3) can be used temporarily
in the common manner, and the broken latches
quickly detached, thus obviating delay and dan-
ger. 60

In Figs. 7 and 8 draw-bars are shown which
are designed to be used with cars differing in
height, which construction locates the ends of
the bars having the receptacles on a horizon-
tal level with each other. 65

In operating the device springs s are not
acted upon, except when coupling the cars, as
shown in Fig. 6, where the hooks of the latches
a are about to catch around pins at x x, as in
Fig. 5, (where the coupling is completed,) in 70
which the springs s have assumed their former
shape. When uncoupling the cars the pins e
at x x are removed, when the cars are drawn
apart without operating the springs.

What I claim as new is— 75

The herein-described car-coupling device,
consisting of the draw-bars D D, receptacles
c' c', holes c c, pins e e and x x, with chains v,
rests y y, latches a a, spring s s, and link n, all
in combination to effect the objects specified. 80

JESSE E. COMBS.
